UNITED STATES PATENT OFFICE.

GEORGE W. MATTERN, OF DAYTON, OHIO, ASSIGNOR TO THE CRAWFORD, McGREGOR AND CANBY COMPANY, OF DAYTON, OHIO, A CORPORATION OF OHIO.

GOLF CLUB.

Application filed February 19, 1923. Serial No. 619,961.

To all whom it may concern:

Be it known that I, GEORGE W. MATTERN, a citizen of the United States, residing at Dayton, in the county of Montgomery and State of Ohio, have invented certain new and useful Improvements in Golf Clubs, of which the following is a specification.

My invention relates to golf clubs and more particularly to a form of handle shaft connection and the method of applying handle shafts, particularly those of the metallic tubular type to metallic golf club heads having the standard or customary form of hosel.

The usual form of tubular metallic handle shafts which have recently come into use are uniformly tapered throughout and at the head engaging end are consequently of much smaller diameter than the socket within the standard form of hosel. To the contrary the usual form of wood handle shaft is provided with a swell or enlargement adjacent to its point of connection with the head, from which swell or enlargement projects the tenon of such size as to completely fill the standard hosel.

Since the advent of the metallic handle shaft many players who possess favorite clubs of proven adaptability and characteristics, desire to have the original wooden handle shaft of such club, replaced with a metallic shaft. The present invention affords a construction and method of adapting the golf club heads having standard enlarged hosels, intended for reception of wooden handle shafts to the smaller and uniformly tapered metallic shafts without causing the adaptation to appear cumbersome or unshapely and without materially changing the weight and balance of the club. In refitting a club by substitution of metallic handle shaft for the original wooden shaft, it is quite important that the weight and balance be preserved. A further advantage of the present construction from the view point of the manufacturer is due to the fact that it enables one type of club head hosel to be readily adapted to either wooden or metallic handle shafts, thereby eliminating the necessity for special dies for the manufacture of hosels of different form and the necessity of carrying large quantities of

heads having different forms of hosels in stock.

The invention involves the use within the standard form of tapered or conical hosel of an insert bushing which conforms exteriorly to the interior of the hosel socket, and interiorly to the tenon portion or head engaging extremity of the metallic handle shaft. This bushing is inserted within the hosel and the handle shaft in turn inserted within the bushing. In the event that the bushing insert is of metallic character, the parts may be integrally united by brazing, welding or other similar means, while if the insert is of other material, the parts are united by cementing or by pinning. After assembly the larger end of the hosel and the bushing which preferably, though not necessarily projects beyond the extremity of the hosel are peripherally reduced into an upwardly tapering or converging form wherein the surface of the hosel merges uniformly with that of the bushing. The result is a rigid and durable connection of maximum strength, but of neat and pleasing appearance of double tapered form affording a medial swell or enlargement of the hosel.

The object of the invention is to afford an improved adapter and method of applying handle shafts to standard golf heads hosels, whereby the connection will be durable of maximum strength and efficiency and unlikely to get out of repair.

A further object of the invention is to provide a mode of operation for economically and efficiently applying uniformly tapered metallic shafts to the standard golf head hosel adapted for reception of wooden handle shafts.

With the above primary and other incidental objects in view as will more fully appear in the specification, the invention consists of the features of construction, the parts and combinations thereof, and the mode of operation or their equivalents as hereinafter described and set forth in the claims.

Referring to the drawings, Fig. 1 is a side elevation of a completed golf club, having the old type of head and hosel to which the metallic shaft has been adapted by the means and method hereinafter described.

Fig. 2 is a sectional view showing the original relative proportions of the parts.

Fig. 3 is a further sectional view of the parts in assembled relation and reduced to 5 ultimate form.

Like parts are indicated by similar characters of reference throughout the several views.

Referring to the drawing wherein is shown 10 the preferred, but obviously not necessarily the only form of embodiment of the invention, 1 is the golf club head of a mashie, mid-iron or niblick type, from which extends the integral conical hosel 2. The hosel 15 2 illustrated in the drawings is of the standard type, adapted for the reception of a wooden handle shaft. This hosel 2 is expanded upwardly so that it is somewhat larger in diameter at its extremity or mouth 20 than at its juncture with the blade 1. In applying a wooden handle shaft to such hosel, the tenon of the shaft would conform to the socket of the hosel 2, and the shaft would be contracted or reduced somewhat 25 beyond the end of the hosel to the desired diameter of the handle shaft. The metallic tubular handle shaft 3, as employed at the present time, is of uniform taper and does not possess the terminal enlargement or swell 30 possessed by the wooden handle shaft and consequently such metallic handle shaft 3 will not conform to nor fit the socket of the standard hosel. To adapt such reduced metallic shaft to the enlarged hosel, there is 35 employed an insert bushing 4, exteriorly tapered to agree with the interior of the hosel socket and having an axial tapered bore 5, with which the metallic tubular handle shaft 3 agrees. The bushing 4 is 40 inserted within the hosel and the handle shaft 3 is in turn inserted within the tapered bore of the bushing and such parts are fixedly united one with another. The bushing 4 is preferably of metal, brass being 45 the usual material. In such case the parts are united by brazing or welding, so that the hosel, the insert bushing and the handle become integrally united. The bushing 4 preferably though not necessarily, extends 50 beyond the extremity or mouth of the hosel 2. The parts having been assembled and united by suitable means as brazing or welding if all of the parts are of metal, or otherwise by cementing, pinning or analogous 55 means, the abrupt shoulders 6 and 7 formed by the extremities of the hosel and bushing respectively are eliminated by reducing the ends of the hosel and bushing to a reverse tapered form 8 converging upwardly to a 60 point of intersection with the handle shaft 3. Such peripheral reduction causes the exterior surface of the hosel to merge uniformly 65 into that of the bushing. That is to say, the bushing and hosel being integral- ly united, the hosel wall is reduced to a

feather edge, at its upper end, such contour being uniformly extended thereby reducing the upper end of the bushing to a substantially feather edge at its juncture with the handle shaft 3. This produces a double 70 tapered form between the handle shaft 3 and the blade 1 of the club, or affords a medial swell 8 of the hosel. It has been found by experiment and comparison that the portion of the bushing 4 remaining after the reduction of the hosel compensates quite accurately for the variation in weight of the metallic and wooden handle shaft so that in the finished product the weight and balance of the original club is retained. 75

From the above description it will be apparent that there is thus provided a device of the character described possessing the particular features of advantage before enumerated as desirable, but which obviously 80 is susceptible of modification in its form, proportions, detail construction and arrangement of parts without departing from the principle involved or sacrificing any of its advantages. 85

While in order to comply with the statute the invention has been described in more or less specific language, as to structural features, it is to be understood that the invention is not limited to the specific details 90 shown, but that the means and construction herein disclosed comprises the preferred form of several modes of putting the invention into effect and the invention is therefore claimed in any of its forms or 95 modifications within the legitimate and valid scope of the appended claims.

Having thus described my invention, I claim:

1. The herein described method of applying handle shafts to golf club heads, consisting in providing a golf club head having a conical hosel, inserting in said hosel a bushing conforming to the interior of the hosel, inserting within the bushing the handle shaft and reducing the end of the hosel and the inserted bushing to a reverse tapered form wherein the exterior contour of the hosel merges uniformly into that of the exposed portion of the insert and the insert contour meets the handle at an acute angle. 105

2. The herein described method of applying handle shafts to golf club heads having conical hosels, consisting in inserting with- 110 in the hosel and around the handle shaft a rigid flexible bushing member which conforms to the interior of the hosel and to the engaged portion of the handle shaft and reducing the extremities of the hosel and in- 115 serted bushing to a contour line intersecting the said members by which the exterior surface of the hosel is made to merge with the exterior surface of the inserted bushing. 120

3. In a construction of the character de- 125

scribed, a golf club head having a hollow hosel, a bushing member inserted in the hosel and projecting therebeyond, and a handle shaft inserted in the bushing, the hosel and projecting portion of the bushing being of substantially double tapered form with the surface of the hosel merging into that of the exposed portion of the bushing.

4. In a construction of the character described, a metallic golf club head having a hosel to receive a handle shaft, a metallic handle shaft of less diameter than the socket of the hosel, a metallic bushing inserted in the hosel around the handle shaft, the extremity of the hosel and insert bushing being tapered upwardly.

5. In a construction of the character described, a metallic golf club head having a hosel to receive a handle shaft, a metallic handle shaft of less diameter than the socket of the hosel, a metallic bushing inserted in the hosel around the handle shaft, the hosel, insert bushing and handle shaft being integrally united one with another.

25 6. The herein described method of applying a metallic handle shaft to a golf club head having a standard hosel adapted for the reception of a wood shaft, consisting in

inserting within the hosel and around the head engaging portion of the metallic handle shaft, a bushing conforming exteriorly to the socket of the hosel and conforming interiorly to the engaged portion of the handle shaft fixedly connecting the said parts each with another, and peripherally reducing the extremity of the hosel and bushing to remove the abrupt shoulder at the juncture of the handle and bushing.

7. The combination with a metallic golf club head having an interiorly tapered standard hosel adapted for the reception of a wood handle shaft, of a metallic handle shaft of reduced diameter at that portion engageable with the head, and a tapered metallic bushing member inserted within the hosel and having therein a tapered bore conforming to the handle shaft to compensate for the variation of diameter of the metallic handle shaft and the socket of the hosel, the extremity of said hosel and insert being peripherally converged upwardly affording a medial swell of the hosel.

In testimony whereof, I have hereunto set my hand this 12th day of February A. D. 1923.

GEORGE W. MATTERN.
